[57] CLAIM

The ornamental design for a coffin, as shown and described.

DESCRIPTION

FIG. 1 is a perspective view of the coffin, showing my new design;

FIG. 2 is an end elevational view thereof, the other end being identical to the end shown;

FIG. 3 is a side elevational view thereof, the other side being identical to the side shown;

FIG. 4 is a top view.

The bottom of the coffin is unornamented.
